CAM GRINDING MACHINE

Russell P. Hook, Worcester, Mass., assignor to
Norton Company, Worcester, Mass., a corpora-
tion of Massachusetts

Application May 18, 1950, Serial No. 162,729

4 Claims. (Cl. 51—101)

1

The invention relates to grinding machines, and more particularly to an improvement in cam grinding apparatus.

One object of the invention is to provide a simple and thoroughly practical cam grinding machine. Another object is to provide an automatic mechanism for separating the cam being ground from the grinding wheel when the nose or high point of the cam is in contact therewith. Another object is to provide an automatic nose lifting device which serves automatically to separate the cam being ground from the grinding wheel when a predetermined portion of the cam, such as the nose or high point of the cam, is in contact with the wheel. Another object is to provide an electrically controlled mechanism for automatically separating the cam being ground from the grinding wheel when the cam is in a predetermined position with respect to the grinding wheel. A further object is to provide a solenoid-controlled spring-actuated wedge for automatically separating the cam being ground and the grinding wheel when nose of the cam is in operative engagement with the grinding wheel. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention:

Fig. 1 is a fragmentary plan view of a cam grinding machine embodying the invention, having a portion of the workhead cover broken away to show details of construction;

Fig. 2 is a cross-sectional view, taken approximately on the line 2—2 of Fig. 1;

Fig. 3 is a fragmentary view of the rock bar and associated parts together with the driving mechanism therefor;

Fig. 4 is a fragmentary plan view, on an enlarged scale, of the solenoid-actuated wedge mechanism for separating the master cam and the follower roller;

Fig. 5 is a fragmentary vertical sectional view, on an enlarged scale, through the master cam and the follower roller spindle and shaft respectively;

Fig. 6 is a fragmentary horizontal sectional view, on an enlarged scale, through the rock bar actuating mechanism; and

2

Fig. 7 is a combined hydraulic and electrical diagram showing the rock bar actuating cylinder and control valve therefor, together with the electrically controlled nose lifting device.

5 A cam grinding machine has been illustrated in the drawings having a base 10 which supports a longitudinally movable work supporting table 11. The table 11 is arranged to slide longitudinally relative to the base 10 on a V-way 12 and a flatway 13 formed on the upper surface of the base 10. The table 11 serves as a support for a rock bar 15 having trunnions 16 formed at the opposite ends thereof which are rotatably supported in bearings (not shown) fixedly supported 15 on the upper surface of the table 11.

A transversely movable wheel slide 20 of the conventional type is arranged to slide transversely on the base 10 on a V-way and a flatway (not shown) formed on the upper surface of the 20 base 10. The wheel slide 20 serves as a support for a rotatable wheel spindle 21 having a grinding wheel 22 mounted on the left-hand end thereof.

A master cam spindle 25 (Fig. 3) is rotatably 25 supported in bearings 26 and 27 which are fixedly mounted on the rock bar 15. The master cam spindle 25 serves as a support for a plurality of master cams 28. The right-hand end of the master cam spindle 25 is provided with a work center 29 which is arranged to support the left-hand end of a camshaft 30 to be ground. A driving dog 31 is provided on the left-hand end of the camshaft 30 may be rotated in timed relationship 35 with the master cam spindle 25.

The master cam spindle and associated parts are contained within a workhead housing 32 which is mounted on the left-hand end of the table 11. An electric motor 33 mounted on top of the housing 32 is provided with a motor shaft 34 which carries a multiple V-groove pulley 35. The pulley 35 is connected by multiple V-belts 36 with a multiple V-groove pulley 37. The pulley 37 is rotatably supported on anti-friction bearings 38 and 39 which are in turn supported by a non-rotatable shaft 40 which is fixedly mounted within the workhead housing 32. A multiple V-groove pulley 41 is formed integral with the multiple V-groove pulley 37 and is connected by 45 multiple V-belts 42 with a multiple V-groove pulley 43. The pulley 43 is journaled on anti-friction bearings 44 which are carried by a sleeve 45 which is fixedly mounted within the workhead housing 32. The pulley 43 is connected by 50 means of a universal joint 46 with a drive shaft 55

47. The drive shaft 41 is connected by means of a universal joint 48 with the left-hand end of the master cam spindle 25 (Fig. 3). It will be readily apparent from the foregoing disclosure that rotation of the motor shaft 34 will be transmitted through the mechanism above described to impart a rotary motion to the master cam spindle 25, the master cams 28, and also the camshaft 30 to be ground.

A master cam follower roller is slidably keyed on a rotatable shaft 51 which is journalled within the workhead housing 32 in fixed relationship with the work table 11. A suitable follower roller indexing mechanism 52 is provided for indexing the master cam roller 50 longitudinally relative to the shaft 51 in timed relationship with the indexing movements of the table 11 automatically to locate the master cam roller 50 opposite a predetermined master cam 28 which corresponds with the cam to be ground. This indexing mechanism is not considered a part of the present invention and consequently has not been illustrated in detail. This mechanism may be substantially identical with that shown in the expired U. S. Patent No. 1,783,755 to C. G. Trefethen and A. G. Belden dated December 2, 1930, to which reference may be had for details of disclosure not contained herein.

A suitable mechanism is provided for moving the rock bar 15 to and from an operative position and to maintain a suitable pressure on the rock bar to maintain the master cam 28 in operative engagement with the follower roller 50. This mechanism may comprise a cylinder 63 and a piston 61 which is operatively connected to rock the rock bar to and from an operative position. It is desirable to rock the bar 15 to an inoperative position so as to separate the master cam 28 from the follower roller 50 before the table 11 is indexed longitudinally. The piston 61 is connected to one end of a piston rod 62. A U-shape frame 63 is clamped in a fixed position on the piston rod 62 by means of nuts 64 (Fig. 6). An upwardly extending actuating arm 65 is fixedly mounted on the rock bar 15 by means of screws 66 and 67. The upper end of the arm 65 is provided with a pair of horizontally extending arms 68 and 69. A pair of tension springs 70 and 71 are connected by screws 72 and 73 to the arms 68 and 69 respectively of the arm 65. The other ends of the springs 70 and 71 are connected to the oppositely projected arms 63a and 63b respectively of the U-shape frame 63. By adjusting the screws 72 and 73, the tension of the springs 70 and 71 may be varied as desired. The arms 68 and 69 of the arm 65 are provided with rollers 74 and 75 respectively which are arranged to be engaged by the U-shape frame 63 when the piston is moved toward the right to shift the rock bar to an inoperative position.

When fluid under pressure is admitted through a port 79 into a cylinder chamber 78 to move the piston toward the right, the U-shape frame 63 will be moved into engagement with the rollers 74 and 75, after which continued movement of the piston 61 toward the right will swing the arm 65 in a clockwise direction (Figs. 2 and 5) to impart a clockwise movement to the rock bar so as to separate the master cam 28 from the follower roller 50 and also to separate the cam being ground from the grinding wheel 22. During this movement of the piston 61, fluid is exhausted from a cylinder chamber 77 through a port 76. The screws 72 and 73 are preferably adjusted so that when the piston 61 is in its extreme left-

hand end position, the U-shape frame will be separated from the rollers 74 and 75 and the tension of the springs 70 and 71 will be sufficient to maintain the master cam 28 in operative engagement with the periphery of the follower roller 50 during rotation of the master cam spindle 25 so as to impart a controlled oscillating movement to the rock bar 15 during a grinding operation.

When the piston 61 moves toward the right, to shift the rock bar to an inoperative position, the U-shape frame 63 moves toward the right and due to the clearance between the frame 63 and the rollers 74 and 75 relieves the tension of the springs 70 and 71 respectively. When the piston 61 and the frame 63 have moved a sufficient distance toward the right, the frame 63 engages the rollers 74 and 75 and rocks the arm 65 and the rock bar 15 in a clockwise direction (Figs. 2 and 5) into an inoperative position.

Similarly when fluid under pressure is admitted through the port 76 into the cylinder chamber 77 to move the piston 61 toward the left, the tension of the springs 70 and 71 serves to maintain the rollers 74 and 75 in operative engagement with the U-shape frame 63 until the master cam 28 moves into operative engagement with the follower roller 50. Continued movement of the piston 61 toward the left causes the U-shape frame 63 to separate from the rollers 74 and 75 and to increase the tension of the springs 70 and 71 to the desired operating tension for maintaining the master cam 28 in operative engagement with the follower roller 50 with the desired pressure during a grinding operation. By utilizing this construction, the extending and contracting of the springs 70 and 71 are reduced to a minimum.

A control valve 85 is provided for controlling the admission to and exhaust of fluid from the cylinder 63. The control valve 85 is preferably a piston-type valve comprising a valve stem 86 having a plurality of spaced valve pistons 87, 88 and 89 formed integrally therewith. Fluid under pressure from any suitable source of supply is conveyed through a pipe 90 into a valve chamber 91 located between the valve pistons 88 and 89. In the position of the valve (Fig. 7) fluid entering the valve chamber 91 passes through a pipe 92 into the cylinder chamber 77 to cause the piston 61 to move into a left-hand end position. During movement of the piston 61 toward the left, fluid within the cylinder chamber 78 exhausts through a pipe 93 into a valve chamber 94 located between the valve pistons 87 and 88 and passes out through a passage 95 and a pipe 96 into the fluid reservoir (not shown). A compression spring 97 surrounding the valve stem 86 serves normally to hold the valve stem 86 in a right-hand end position. An electric solenoid 98 is provided when, when energized, serves to shift the valve stem 86 into a left-hand end position.

It is desirable to provide an automatic control for the solenoid 98 so that after the cam being ground has rotated a predetermined number of rotations in operative engagement with the grinding wheel, the solenoid 98 will be deenergized to cause fluid under pressure to pass into the cylinder chamber 78 to move the piston 61 toward the right thereby rocking the rock bar 15 in a clockwise direction to an inoperative position. In order to facilitate automatic control of the valve 85, an electric counter 100 is provided. This electric counter 100 may be one of the commercial varieties now on the market, for example,

as shown a Microflex electric counter such as manufactured by the Signal Electric Corporation of Moline, Illinois. Electric power is supplied from any suitable source such as indicated by the power lines 101. The rock bar 15 is provided with an arm 102 (Figs. 2, 5 and 7) which is arranged to rock in the path of an actuating roller 103 which is mounted on the actuating arm 104 of a normally closed limit switch 105. The arm 102 is preferably arranged so that during the normal oscillation of the rock bar during each rotation of the master cam 28, the limit switch 105 will be opened to impart an impulse to the counter 100. After a predetermined number of impulses on the counter, a circuit is broken to deenergize the solenoid 98 thereby releasing the compression of the spring 97 which moves the valve stem 86 toward the right into a right-hand end position. When the valve stem is in the right-hand end position fluid under pressure in the pipe line 90 passes through the valve chamber 94, through the pipe 93 into the cylinder chamber 78 to move the piston 61 toward the right (Fig. 7) thereby rocking the arm 65 and the rock bar 15 in a clockwise direction to separate the master cam 28 from the follower roller 50 and at the same time to separate the cam being ground from the grinding wheel 22.

It has been found desirable in the grinding of cams to separate the cam being ground from the grinding wheel when the nose or high point of the cam is in contact with the grinding wheel thereby eliminating slight reentrant curve on the surface of the cam being ground when the cam and grinding wheel separate. This is preferably accomplished by means of an automatically controlled mechanism comprising a follower, such as a slidably mounted plunger 106 having a tapered end portion 107. The slidably mounted plunger 106 is supported in a bracket 112 mounted with-in the upper portion of the workhead housing 32. A compression spring 108 is provided which is arranged normally to tend to move the plunger 106 toward the right. A solenoid 109 is provided which, when energized, serves to move the plunger 106 toward the left into an inoperative position as illustrated in Fig. 6. The tapered face 107 of the plunger 106 is arranged to engage cam faces 110 and 111 fixedly mounted on the upper end of the arm 65. When the solenoid 109 is deenergized, the release compression of the spring 108 serves to move the plunger 106 toward the right so that the tapered portion 107 thereof moves into the full line position 107a (Fig. 4) into engagement with the cam face 110. The compression of the spring 108 is not strong enough to rock the rock bar so as to separate the master cam 28 from the roller 50 but serves to hold the arm 65 as the master cam rotates so that when the high point of the master cam is in engagement with the grinding wheel, the taper 107 will be moved into engagement with the cam face 111, as shown in Fig. 1. The taper 107 holds the cam 111 in this position and does not allow the arm 65 to rock in a counter-clockwise direction after the high point has been passed.

In order that the plunger 106 may be operated on the last rotation of the cam being ground, the solenoid 109 is preferably connected so as to be actuated by the electric counter 100. The electric counter 100 is preferably adjusted so that it receives the last impulse when the high point of the cam being ground approaches contact with the grinding wheel. As the counter 100 counts out, it serves to break a circuit there-

by deenergizing the solenoid 109 so as to allow the tapered end 107 of the plunger 106 to move under the influence of the spring 108 into operative engagement with the cam faces 110 or 111 so that the arm 65 will be locked when it reaches its extreme throw in a clockwise direction when the high point of the master cam is in engagement with the follower roller 50. At the same time the solenoid 109 is deenergized, the solenoid 98 is also deenergized so that the released compression of the spring 97 shifts the valve stem 86 into a right-hand end position so that fluid under pressure within the pipe 90, passes through the valve chamber 94, through the pipe 93, the port 79 into the cylinder chamber 78 to move the piston 61 toward the right. During the initial movement of the piston 61 toward the right, the tension of the springs 70 and 71 is gradually released during the last motion period until the U-shape frame 63 moves into engagement with the rollers 74 and 75. Continued movement of the piston 61 toward the right then serves to rock the arm 65 and the rock bar 15 in a clockwise direction (Figs. 2 and 5) to separate the master cam 28 from the follower roller 50 and to separate the cam being ground from the grinding wheel 22. During the last motion interval before the U-shape frame 63 engages the rollers 74 and 75, the plunger 107 has moved into engagement with the cam faces 110 and thereafter into engagement with 111 to lock the lever 65 when the high point of the master cam 28 moves into engagement with the follower roller 50. It will thus be seen that provision has been made for automatically separating the master cam from the follower roller when the high point of the master cam is in engagement with the follower roller and when the high point of the cam being ground is in engagement with the grinding wheel.

The arm 102 is preferably adjustably mounted on the rock bar 15 by means of a pair of screws 115 and 116 which pass through elongated slots (not shown) which allow the arm 102 to be adjusted vertically so as to vary the time at which the limit switch 105 is opened during the normal oscillation of the rock bar 15. As above mentioned the arm 102 is preferably positioned so as to open the limit switch 105 slightly before the high point of the master cam 28 is engaged with the follower roller 50.

The operation of this improved cam grinding apparatus will be readily apparent from the foregoing disclosure. A control switch 117 in the power lines 101 serves to render the electric circuit operative. When a grinding operation is started, the switch 117 is closed to energize the solenoid 98 so that fluid under pressure is passed into the cylinder chamber 77 to cause the piston 61 to move into a left-hand end position thereby swinging the rock bar 15 in a counter-clockwise direction to position the master cam 28 in operative engagement with the follower roller 50. At the same time the solenoid 109 is energized to withdraw the plunger 106 so that the taper 107 is out of engagement with the cam faces 110-111 thus allowing free movement of the arm 65. The grinding operation continues for a predetermined number of oscillations of the rock bar 15. That is a predetermined number of rotations of the master cam 28 and the cam being ground according to the setting of the adjustable electric counter 100. After a predetermined number of oscillations of the rock bar 15, the counter 100 breaks a circuit to deenergize the solenoid 109

thus releasing the compression of the spring 103 to move the taper 107 into engagement with the cam faces 110—111. At the same time the solenoid 98 is deenergized and the release compression of the spring 97 shifts the valve stem 86 toward the right so that fluid under pressure is passed from the pipe 90 through the valve 65, the pipe 93, the port 79 into the cylinder chamber 78 to move the piston 61 toward the right thereby rocking the rock bar 15 in a clockwise direction to separate the master cam 28 from the follower roller 51 when the high point of the master cam is in engagement therewith and when the high point of the cam being ground is in engagement with the grinding wheel.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a cam grinding machine having a pivotally mounted rock bar, a rotatable master cam spindle thereon, a master cam on said spindle, a follower roller cooperating with said master cam, means to rotate said spindle so as to impart a controlled oscillation movement to said rock bar, a cam on said rock bar, a follower movable into engagement with said cam, a compression spring normally tending to move said follower into engagement with said cam, said follower and cam being shaped so that the follower when in engagement with said cam serves to limit the rocking movement of said rock bar, a solenoid normally to maintain said follower in an inoperative position, and electrical control means to deenergize said solenoid after a predetermined grinding operation has been completed to allow the follower to move into engagement with said cam to facilitate separation of the master cam and follower roller when the high point of the master cam is in engagement with the follower roller.

2. In a cam grinding machine having a longitudinally movable table, a rock bar pivotally mounted on said table, a rotatable master cam spindle on said rock bar, a master cam on said spindle, a rotatable follower roller on said table, means rotatably to support a camshaft to be ground in axial alignment with the spindle, means to rotate said spindle and camshaft to impart a controlled rocking movement to said rock bar, an arm on said rock bar, yieldable means acting on said arm to maintain the master cam in operative engagement with the roller during a grinding operation, a cam on said arm, a slidably mounted follower arranged to move into engagement with said cam, a compression spring normally to maintain said follower in engagement

with said cam, an electric solenoid which when energized serves to hold the follower in an inoperative position, and an electric counter actuated by the oscillation of the rock bar to deenergize said solenoid after a predetermined number of oscillations of the rock bar to stop the oscillation of the rock bar when the high point of the master cam is in engagement with the follower roller.

3. In a cam grinding machine having a longitudinally movable table, a rock bar pivotally mounted on said table, a master cam spindle on said rock bar, a master cam on said spindle, a follower roller on said table, means rotatably to support a camshaft to be ground in axial alignment with said spindle, means to rotate said spindle to rotate the camshaft to be ground and to impart a controlled rocking movement to said rock bar, an upwardly extending arm on said rock bar, yieldable means acting on said arm to maintain the master cam in operative engagement with the follower roller during a grinding operation, a piston and cylinder to rock said arm and rock bar to an inoperative position, a solenoid-actuated control valve therefor, a cam on said arm, a spring pressed taper plunger arranged to engage said cam, a solenoid normally to hold said plunger in an inoperative position, and an electric counter actuated by oscillation of the rock bar to deenergize both of said solenoids after a predetermined number of oscillations of the rock bar to stop the oscillation of the rock bar when the high point of the master cam is in engagement with the follower roller and thereafter to rock the rock bar to an inoperative position.
4. In a cam grinding machine having a longitudinally movable table, a rock bar pivotally mounted on said table, a master cam spindle on said rock bar, a master cam on said spindle, a follower roller on said table, means rotatably to support a camshaft to be ground in axial alignment with said spindle, means to rotate said spindle to rotate the camshaft to be ground and to impart a controlled rocking movement to said rock bar, an upwardly extending arm on said rock bar, yieldable means acting on said arm to maintain the master cam in operative engagement with the follower roller during a grinding operation, a piston and cylinder to rock said arm and rock bar to an inoperative position, a solenoid-actuated control valve therefor, a cam on said arm, a spring pressed taper plunger arranged to engage said cam, a solenoid normally to hold said plunger in an inoperative position, an electric counter operatively connected to control both of said solenoids, and a limit switch actuated by each oscillation of the rock bar to impart an impulse to said counter, said counter serving after a predetermined number of oscillations of the rock bar to stop the oscillation of the rock bar when the high point of the master cam is in engagement with the follower roller and thereafter to rock the rock bar to an inoperative position.

RUSSELL P. HOOK.
